TREAD-GRATING UNIT

Ernest C. Liskey, Jr., Severna Park, Md.

Application April 11, 1958, Serial No. 50,444

Term of patent 14 years

(Cl. D13—1)

Figure 1 is a perspective view of a tread-grating unit showing my new design; and

Figure 2 is an end elevation thereof.

The side and end of the unit, not shown, are like the side and end of the unit which is shown.

I claim:

The ornamental design for a tread-grating unit, as shown and described.
